(57) **CLAIM**

We claim the ornamental design for a disposable cup for urinalysis, as shown and described.

DESCRIPTION

FIG. 1 is a perspective view of a disposable cup for urinalysis, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof; and,

FIG. 9 is a partial sectional view thereof taken along line 9-9 of FIG. 8.

The broken lines in the drawings show portions of the disposable cup for urinalysis that form no part of the claimed design.

1 Claim, 8 Drawing Sheets
